UNITED STATES PATENT OFFICE.

GEORGE H. HOLLAND, OF ST. LOUIS, MISSOURI, ASSIGNOR TO THE BRIDGE & BEACH MANUFACTURING COMPANY, OF SAME PLACE.

DESIGN FOR A STOVE.

SPECIFICATION forming part of Design No. 22,576, dated June 27, 1893.

Application filed May 26, 1893. Serial No. 475,645. Term of patent 7 years.

To all whom it may concern:

Be it known that I, GEORGE H. HOLLAND, a citizen of the United States, residing at St. Louis, State of Missouri, have invented and 5 produced a new and original Design for Stoves, of which the following is a full, clear, and exact description, reference being had to the accompanying drawing, wherein the figure represents a stove ornamented with my new design.

This design relates particularly to an upright, cylindrical-shaped stove, and consists in the shape and surface ornamentation of its several component parts as will hereinafter be described.

The base is circularly shaped, being ornamented at its sides with flutes, some of which are extended over their companions in the form of scrolls. Projecting from the front of 20 this base is a name-plate, the ends of which are in the representations of scrolls. The legs project from the lower portion of the base and are ornamented on their outer curved portion by a spray of leaves. The ash-pit 25 door is provided with the usual draft openings in its lower portion, around which are scrolls. Above these draft openings, is a raised panel in the form of a nameplate. The sides and top of the ash-pit door are formed 30 converging and are ornamented with flutes running to a number of scrolls arranged at the edges. On the right side of the ash-pit door is a raised panel forming a name or number plate. Above this name plate, is a molding 35 which extends forward and up to the top of the ash-pit door, where it is curved upwardly and across to form a semi-circular panel, in which a medallion is arranged, said medallion being surrounded by a spray of 40 leaves whose stems cross each other there-beneath. Above this semi-circular panel, is a

raised panel, the lower edge of which is curved, to conform to the curvature of the semi-circular panel, this upper panel being ornamented by two sprays of leaves.

45

At the upper portion of the right side of the stove, is a door in the form of a panel, the sides of which are fluted, and ornamented with scrolls at its outer edge, which scrolls are the continuation of some of the flutes. 50 The panel is ornamented with the representation of a branch of grape-vine, with its leaves and tendrils and a bunch of grapes.

At the left side of the stove, above and below the molding, are two raised panels. 55

The top flange extend downwardly and outwardly over the body-portion of the stove, its sides being ornamented with flutes, some of which are continued in the form of scrolls extending over their companions. The top 60 is convexed in shape and ornamented in the representation of a web-work of intertwining leaves and stems. Projecting from this top is an urn, having the usual base, its lower body-portion being fluted and its tapering top 65 portion being ornamented by surrounding beads, above which, semi-circular beads are arranged. Rising from these semi-circular beads, is a dome-shaped extension, which has projecting from its top a flower having irregularly projecting leaves or petals. 70

What I claim is—

The herein-described design for stoves, substantially as shown.

In testimony whereof I hereunto affix my 75 signature, in presence of two witnesses, this 17th day of May, 1893.

GEO. H. HOLLAND.
